UNITED STATES PATENT OFFICE.

REINHARD KLINGELHÖFFER, OF WERDEN-RUHR, GERMANY, ASSIGNOR TO FRIED. KRUPP AKTIENGESELLSCHAFT, OF ESSEN-ON-THE-RUHR, GERMANY.

CONDENSING LOCOMOTIVE.

Application filed September 17, 1923, Serial No. 663,296, and in Germany February 13, 1923.

This invention relates to condensing locomotives. With locomotives of this kind carrying on their tender auxiliary engines the exhaust-steam of which is led to the condenser, while the condenser is mounted on the locomotive, the driving steam has to be conducted from the locomotive to the tender and the exhaust-steam back to the locomotive into the condenser. If the auxiliary engine is arranged on the locomotive and the condenser on the tender, the exhaust-steam of the auxiliary engine must be conducted to the tender. In both cases, it is necessary to use between the locomotive and tender flexible pipe-couplings which may be either hose or pipe connections with ball joints and when a state of vacuum exists in these connections they are kept air-tight with difficulty. Therefore, as soon as a partial vacuum arises in the exhaust conduit and consequently in the flexible pipe connections by a direct connection with the condenser, the danger exists of air being sucked into the condenser whereby the efficiency of the entire machine-plant is impaired.

This drawback is obviated according to the invention by constructing the auxiliary engines as reaction engines (for example as reaction turbines) so that the flexible pipe coupling between the locomotive and tender, in which a pressure above atmospheric will now prevail, is no longer connected directly to the condenser. Before entering the condenser, the exhaust-steam may then still be utilized for doing work in a feed water heater or in a low pressure turbine and the like.

An embodiment of the subject matter of the invention is illustrated in the accompanying drawing, in which:

Fig. 1 is a side elevation of the locomotive and tender, and

Fig. 2 a section along the line 2—2 of Fig. 1.

The live steam coming from the locomotive boiler flows through a pipe *a* (Fig. 1), a flexible pipe *b* and a pipe *c* to a reaction turbine *d*, driving the same. The turbine actuates a blower *f* through the intermediary of a gearing *e* (Fig. 2). The exhaust-steam 45 discharged by the turbine *d* at a pressure slightly above atmospheric pressure returns through a pipe *g* and a flexible pipe *h* to the locomotive. With the embodiment shown, the exhaust-steam is then caused to 50 flow through a feed water heater *n* and from same through a controlling valve *i* and a pipe *p* into the condenser *k*. The controlling valve *i* is regulated so as to hold the exhaust-steam conduit under a certain 55 pressure as soon as the reaction turbine *d* is working. Instead of utilizing the exhaust-steam for heating the feed water, it 60 may also be used in any other way.

Claim.

In a condensing locomotive, an auxiliary engine, a flexible pipe connecting said auxiliary engine with the condenser of the locomotive, and a regulating valve inserted in the pipe connection between the flexible 70 pipe and the condenser, whereby the steam in the flexible pipe can be maintained at a pressure higher than atmospheric pressure.

The foregoing specification signed at Cologne, Germany, this 27th day of July, 1928.

REINHARD KLINGELHÖFFER.
